UNITED STATES PATENT OFFICE.

LOUIS KOLL, OF PEORIA, ILLINOIS, ASSIGNOR TO STUBER & KUCK CO., OF PEORIA, ILLINOIS, A CORPORATION OF ILLINOIS.

CAN.

Application filed April 11, 1925. Serial No. 22,470.

This invention has reference to improvements in cans or receptacles for storage of liquids. More particularly, the invention has to do with pouring spouts or nozzles 5 through which the contents of cans or receptacles are discharged.

One of the objects of the invention is to provide a can or other container with a spout or nozzle including an air vent peculiarly placed by which the pouring out 10 of the contents may be facilitated.

Another object is that of providing an air vent in the structure of a tubular spout or nozzle of a can outward from the nozzle itself 15 and the further provision of a longitudinally extending groove in said nozzle to conduct a liquid along the latter that may chance to escape through said vent.

The invention relates, further, to certain 20 details of construction as will be pointed out herein and form the subject of some of the appended claims.

In the appended drawing forming part 25 hereof,

Figure 1 is a vertical section of a portion of a can including a well known threaded collar secured thereto, a closure and the spout or nozzle of my invention being shown in connection therewith. Figure 1^a 30 is an elevation of a modified form of a nozzle.

Figure 2 is a longitudinal section of the spout or nozzle.

Figure 3 is a plan of the same as viewed 35 at its under side.

Figure 4 shows the same as seen from above.

Figure 5 shows the spout or nozzle in perspective, and Figures 6 and 7 are modifications of the nozzle construction.

A portion of a can or container is illustrated at 1 in Figure 1. It has an opening 2 in one of its walls covering which is a threaded collar 3 of a well known form 45 adapted to receive a similarly threaded cap 4 having an opening 5 in its top.

A spout or nozzle is arranged to be used in connection with the described parts and comprises a disc 6 from which extends preferably at an oblique angle to the plane thereof a tubular portion 7 which may be tapered from its base at said disc to its free end. The nozzle is adapted for two positions as shown in Figure 1. That is to say, it may 50 be used for pouring out the contents of the

can, the dotted lines showing its position for that purpose, or it may be dropped into the can for storing or shipping as shown in full lines. When used in the manner last described, a gasket of suitable material 8 60 is first placed upon the collar 3, the tubular portion 7 being passed through it with the disc 6 resting thereon. Upon the said disc is then placed a disc 9 of suitable material forming a tight packing, and this is followed 65 by the screw cap 4 to effectually prevent leakage. When used for pouring, the spout or nozzle with the disc 6 rests upon the said gasket 8 but of necessity the disc 9 is eliminated and if desired a second gasket 70 such as 8, not shown, may replace said disc.

The spout or nozzle is of peculiar form it being observed in the last four figures of the drawing that the tubular part 7 is provided with a groove 10 extending longitudinally along the same as by creasing the metal lengthwise for example. In the disc 6 is an opening 11 substantially in line with the said groove 10 and, preferably, a strip of metal 11' lies across or bridges the groove 80 at the base of the part 7 forming a tight closure with the nozzle and said disc but leaving a clear opening behind it as in Figure 2. The disc may be open the full diameter of the base of the tubular part 7, or as shown in Figure 3, the opening may be somewhat constricted as shown at 12 in that figure and in Figure 2. But in any event this opening is separate from the vent 11 so that in the act of pouring the liquid will 85 escape through the opening 12 while the air to take the place of the liquid in the can may enter through the opening 11. If by chance the can is tipped too high at any time in the pouring act any liquid that may 90 escape by way of the said opening 11 will enter the groove 10 and find its way to the extremity of the nozzle where it will be deposited into the receiver being supplied 95 from the nozzle itself.

The metal between the vent opening and the opening 12 serves to limit the amount of liquid flowing into the nozzle, the said opening 12 being about equal in extent to the opening at the discharge end of the nozzle but this is mere choice.

In the modification of the nozzle, Figure 1^a, the vent denoted at 11^a is made in the rear wall, said nozzle being indicated in said figure by 7'.

Again, in Figures 6 and 7 the collar 3' rearward of the nozzle designated by 7' is notched at 3² while the cap 4' is notched at 4² to register therewith and if the ring 8 of the other figures is employed, designated as 8', it may be similarly notched as at 8². This permits the air to enter the container, not shown in the figures last named. In said figures the disc portion 7² is of less diameter than the inner diameter of the cap 4' so that a passage is created between it and the latter, the said notches 4², 8² and 3² lying substantially in line creating the desired air passage, the disc 9, Figure 1, serving as before to close the same when the device is assembled for shipping or storage.

Of importance in my form of device is the fact that while the tubular portion or spout 7 is constructed so as to be entirely open throughout, loss of liquid when the spout is inverted is prevented by the use of the closure-disc 9 for said spout and the threaded collar 3 while the receptacle is in storage or shipment.

I claim:

1. In combination with a receptacle for a liquid including an opening for discharge of the liquid, a separate spout or nozzle invertible in position whereby to be suspended within the receptacle or to be erected upon the same, said nozzle including an annular extended flange at its base covering the

opening, there being an air vent in said annular flange communicating with the interior of the receptacle through the said opening thereof, there being a depression in the outer wall of the nozzle extending longitudinally of the same substantially in line with the air vent, and means to secure the annular flange upon the receptacle.

2. A nozzle for the purposes described including a spout portion having an open groove extending therealong on its outer side, and also including an annular flange portion at and extending laterally beyond the base of said spout, there being an opening in the said flange portion leading into said groove, and a member covering a part of said groove immediately adjacent the said annular portion forming a pocket at said opening.

3. A nozzle of the type described including a tubular portion depressed along its wall forming a groove on the outer side, the base of the nozzle terminating in an annular flange, there being an opening in the flange substantially in line with the said depression or groove, and a part bridging the groove adjacent the flange forming a passageway from the opening to the exposed portion of said groove.

In testimony whereof I affix my signature.

LOUIS KOLL.
